DESIGN FOR A GRAVE MARKER

Frederick F. Florig, Pittsburgh, Pa., assignor to
Jas. H. Matthews & Company, Pittsburgh, Pa.,
a corporation of Pennsylvania

Application November 7, 1938, Serial No. 80,912

Term of patent 14 years

To all whom it may concern:

Be it known that I, Frederick F. Florig, a citizen of the United States, residing at Pittsburgh, county of Allegheny, and State of Pennsylvania, have invented a new, original, and ornamental Design for a Grave Marker, of which the following is a specification, reference being had to the accompanying drawing, forming part thereof, in which Fig. 1 is a top plan view of a grave marker showing my new design, and Fig. 2 a side elevation thereof, partially in section.

The characteristic features of my design con-

sist in a rectangular grave marker having a mottled sloping border enclosing a central panel, said border having a relatively thin projecting base portion and a rib-like border element adjacent the central panel, said border element having drooping leaf forms extending therefrom and superimposed upon the mottled surface of the border, as shown.

I claim:

The ornamental design for a grave marker, as shown and described.

FREDERICK F. FLORIG.
